UNITED STATES PATENT OFFICE.

PAUL THEODORE HAHN, OF WOODCLIFF, WEEHAWKEN, NEW JERSEY.

PRINTING DEVICE.

No. 823,042.

Specification of Letters Patent.

Patented June 12, 1906.

Application filed November 13, 1905. Serial No. 287,012.

To all whom it may concern:

Be it known that I, PAUL THEODORE HAHN, a citizen of the United States, residing at Woodcliff, Weehawken, in the county of Hudson and State of New Jersey, have invented certain new and useful Improvements in Printing Devices, of which the following is a specification, such as will enable those skilled in the art to which it appertains to make and use the same.

This invention relates to devices or means for printing on wrapping-paper; and the object thereof is to provide an improved device of this class which is designed for use in connection with a roll of wrapping-paper from which strips or sections of paper may be drawn for use in the usual manner, a further object being to provide a device of the class specified for use in retail shops and similar places where wrapping-paper is usually kept in rolls and by means of which any desired advertisement may be printed on separate strips, sheets, or sections of the paper as they are drawn from and detached from the roll.

The invention is fully disclosed in the following specification, of which the accompanying drawings form a part, in which the separate parts of my improvement are designated by suitable reference characters in each of the views, and in which—

Figure 1 is a side view of a part of a main frame and showing a part of a roll of paper mounted therein and showing also one form of my improved printing device; Fig. 2, a sectional plan view of the device as shown in Fig. 1, the line of the section being that designated as 2 2 in Fig. 1; Fig. 3, a view similar to Fig. 1, but showing the printing device in transverse section, the section being taken on the line 3 3 of Fig. 2; Fig. 4, a section on the line 4 4 of Fig. 2 looking in the direction of the arrow x; Fig. 5, a view similar to Fig. 4, but looking in the opposite direction and showing only part of the construction shown in Fig. 4; Fig. 6, a section on the line 6 6 of Fig. 4; Fig. 7, a view similar to Fig. 1, but showing a modification for printing in different colors with part of the construction broken away; Fig. 8, a plan view of the device as shown in Fig. 7 with part of the construction broken away, and Fig. 9 a section on the line 9 9 of Fig. 7.

In the practice of my invention, as shown in Figs. 1 to 6, inclusive, I provide a main frame comprising side members a and a top member a², and said frame may be provided

with any desired form of base or may be supported in any preferred manner. At the top portion of the main frame and at the back thereof is mounted a transverse shaft b, one end of which is provided with an arm b², rigidly connected therewith, and said shaft is provided with supports b³, which are suspended from the top portion of the main frame and the front portions of each of which is segmental in form and provided with ratchet-teeth b⁴, which form segmental ratchets, and the shaft b is also provided centrally with a forwardly-directed arm b⁵.

Mounted on the end portions of the shaft b within the sides of the main frame is a main printing-frame c, comprising side members c², and springs c³ are coiled on the end portions of the shaft b, and one end of said springs is secured to the supports b³ and the other end thereof to the side members c² of the main printing-frame, and these springs c³ serve to tensionally hold the main printing-frame in its highest position, as shown by the dotted lines c⁴ in Fig. 1, in which position the front movable portion of said main printing-frame presses on the top a² of the main frame of the device.

Mounted transversely of and in the front portion of the main frame is a main printing-cylinder d, the ends of which are provided with wheels d², formed integrally therewith or rigidly connected therewith, and said printing-cylinder is provided centrally with a type-plate d³, on which the type of any desired advertisement may be placed.

Pivoted in the main printing-frame c is an inking or supplemental printing-frame e, said supplemental printing-frame being mounted on a transverse rod e², the ends of which are supported in the sides of the main printing-frame c, and said supplemental printing-frame comprises end portions e³, a top portion e⁴, and a downwardly-directed back plate e⁵, provided with an aperture e⁶ to receive the arm b⁵ on the shaft b. Pivoted forwardly of the ratchet members b⁴ are dogs f, having teeth adapted to engage the ratchets b⁴, and pivoted to each of said dogs is a rod f², and the forward ends of the rods f² are pivoted to the end members of the supplemental printing-frame e, and springs f³ are employed to hold the dogs f in normal engagement with the ratchet members b⁴. Each end member e³ of the supplemental printing-frame e is provided at the bottom thereof with a forwardly-directed arm g, having a

transverse head g^2 , and each of said end members e^3 of the supplemental printing-frame e is provided on the opposite sides of the arm g with forwardly-directed fingers g^3 , and mounted in the supplemental printing-frame is an inking-roller e^7 , having a pad or cushion e^8 , and in practice the ink may be applied to said pad or cushion in any desired manner. Each end of the printing-cylinder d is provided with a cam-hub d^4 , having a cam projection d^5 at one side thereof, and these cam-hubs d^4 or the projections d^5 thereof operate in practice on the heads g^2 of the arms g , and each end of the printing-cylinder d is also provided with a pivoted pawl d^6 , and the ends of said printing-cylinder are also provided with annular raised portions d^7 , having recesses d^8 , in which the pawls d^6 are pivoted and by means of which the movement of said pawls is limited.

Mounted on the ends of the shaft d^9 of the printing-cylinder and rigidly secured thereto are wheels h , having cam-hubs h^2 , similar to the cam-hubs d^4 , on the ends of the printing-cylinder, and the cam-hubs h^2 are provided with cam projections h^3 , similar to the cam projections d^5 , and which also operate in connection with the heads g^2 of the arms g . The wheels h are also preferably provided with annular raised portions h^4 , having recesses h^5 , in which are pivoted pawls h^6 , similar to the pawls d^6 , and the pawls h^6 operate in connection with the outer fingers g^3 on the end members e^3 of the supplemental printing-frame, while the pawls d^6 operate in connection with the inner fingers g^3 of the end members of the supplemental printing-frame, and the wheels h are also preferably provided at a predetermined point on their outer edges with cam projections h^7 . Wound on the opposite ends of the rod or shaft e^2 , on which the supplemental printing-frame e is mounted, are springs h^8 , and one end of these springs is secured to the supplemental printing-frame and the other to the main printing-frame, and said springs normally serve to hold the supplemental printing-frame in its raised position or out of contact with the printing-cylinder.

The arm b^2 on the shaft b need not necessarily be employed in all cases, but is preferably employed in large machines in order that an operator may conveniently manipulate the device, and in practice a roll of paper (partially shown at i) is mounted in the main frame, and whenever it is desired to tear off a strip or sheet thereof in the usual manner and it is desired to print an advertisement on said strip or sheet and the inking-roller e^7 having been previously inked the main printing-frame is depressed by pulling forwardly and downwardly on the arm b^2 if said arm be employed. This operation forces the supplemental printing-frame e downwardly, so that the inking pad or cushion thereon will come in contact with the

type-plate d^9 on the printing-cylinder d , and at the same time the printing-cylinder is forced downwardly onto the roll of paper, and when the parts are in this position a strip or sheet of the paper may be pulled out or off of the roll and torn off in the usual manner, and the desired advertisement will be printed thereon. If the arm b^2 is not employed, the supplemental printing-frame may be depressed by means of a handle i^2 , connected therewith, by pressing downwardly and backwardly on said handle, and this will result in depressing the supplemental printing-frame e , as hereinbefore described, and also in depressing the main printing-frame so that the printing-cylinder d will come in contact with the paper-roll i . In the operation of depressing or turning the supplemental printing-frame e above described the dogs f are released from the ratchets b^4 , as shown in Fig. 4, which enables the main frame to be depressed, and as soon as the pressure on the handle i^2 of the supplemental printing-frame is released the springs f^3 force the dogs f back into engagement with the ratchet b^4 . The dogs f and rod f^2 , connected therewith, are adapted to be employed where the main frame is of sufficient weight to operate by gravity, and in the rotation of the wheels h^2 after the printing has been accomplished the projections h^7 thereon would force the main frame upwardly, and the dogs f being moved upwardly on the segmental ratchet b^4 will hold the main frame in the raised position, and the type would be removed from the paper, as will be understood.

The arrangement shown in the drawings of the arms g and pawls d^6 is utilized to increase the space between two impressions of the type whenever it is desired to print continuously on a strip of paper drawn from the roll i , and the operation of these parts is as follows: Supposing the pawls d^6 and h^6 be in the positions shown in Figs. 4 and 5 and a strip of paper to be drawn from the roll i , the withdrawal of the said strip would rotate the wheels d^2 of the printing-cylinder d , but would not rotate the wheels h , for the reason that the pawls h^6 thereon were in engagement with the fingers g^3 of the arms g ; but when the wheels d^2 are so rotated the cam d^5 thereof, which is preferably mounted thereon slightly in advance of the pawls d^6 , coming into contact with the heads g^2 would force the supplemental frame e backwardly and upwardly, thereby releasing the pawls h^6 from the corresponding fingers g^3 , and the wheels h may then be rotated in the withdrawal of the sheet of paper. After the pawls h^6 have been released, as just described, the arms g are again forced inwardly to the concentric surface of the cam-hubs d^4 and the pawls d^6 on the wheels d^2 are engaged by the corresponding fingers g^3 , and the printing-cylinder d is thereby held against rotation.

tion. When the wheels h have been rotated approximately through their full rotation, the cams h^3 thereon force the arms g outwardly, as previously described, thereby releasing the pawls d^6 from the corresponding fingers g^3 , by which they were engaged, and the rotation of the printing-cylinder d is again made possible; but at approximately this same time the pawls h^6 are again engaged 5 by the corresponding fingers g^3 , and the wheels h are locked against rotation. Assuming that in the first rotation of the printing-cylinder an impression had been made by the type thereof upon the paper being without drawn, if the cylinder d were permitted to continue its rotation another impression would be made, the beginning of which would be a distance equal to the circumference of the wheels d^2 ; but by means of my arrangement 10 the wheels d^2 , being locked against rotation until the wheels h have accomplished a full rotation, the distance between the beginning of the impressions is thereby doubled, or nearly so, according to the relative positions 15 of the pawls d^6 and h^6 , and this locking and releasing of the printing-cylinder and the wheels h occur alternately, as will be understood, and if the wheels h be rotated backwardly manually, thereby changing the 20 relative positions of the pawls d^6 and h^6 , the distance between the impression is lessened, as will be seen. When sufficient paper has been drawn from the roll i , releasing the pressure 25 on the arm b^2 or handle i^2 will when the springs c^3 are employed permit the main frame c to rise and no printing is accomplished, even though more paper be drawn out, or if the springs c^3 be not employed the frame c is raised by means of the projections 30 h^7 on the wheels h , and the said frame is held in its raised position by means of the dogs f .

In Figs. 7, 8, and 9 of the drawings I have shown a modification of the construction heretofore described, said modification being 45 made to permit of printing in two colors, and in this form of construction I provide the main printing-frame c and spring c^3 therefor, as well as the printing-cylinder d , with the parts heretofore described, and in addition 50 with supplemental wheels k and k^2 and the inking-frame e is also employed, as well as the inking-roller e^7 therein; but the inking-roller is adapted to move outwardly against the pressure of a spring k^3 , as clearly shown 55 in Figs. 7 and 8, and is provided with a wheel k^4 at each end thereof, which wheels are adapted to rotate upon the wheels k^2 of the printing-cylinder d .

As shown in Fig. 7 of the drawings, the 60 inking-cylinder e is provided with a segment-gear m , engaging a similar segment-gear m^2 on a supplemental inking-frame m^3 , which is pivotally mounted, as shown at m^4 , to the main frame c , and the supplemental inking-frame m^3 is provided with an inking-roller m^5 ,

which is adapted to be moved outwardly against the action of a spring m^6 , as clearly shown in Figs. 7 and 9 of the drawings, and the inking-roller m^5 is also provided with a wheel m^7 at each end thereof, and said wheels m^7 are adapted to rotate on the wheels k of the printing-cylinder. 70

As clearly shown in Figs. 7 and 9, the wheels k and k^2 are provided at intervals with recesses n and n^2 , into which the corresponding wheels m^7 and k^4 are adapted to enter, this operation being made possible by means of the springs k^3 and k^6 , and when the wheels of one of the inking-rollers enters the corresponding recesses the said inking-roller is forced inwardly into contact with the type-face, said type, however, not being shown in Fig. 7, although clearly shown in Fig. 9, and in this manner the inking of a line of type is performed with an ink of one color 80 by means of the one inking-roller and another line of type may be inked another color by means of the other inking-roller, the recesses in the wheels k and k^2 being arranged therein in order to accomplish this result. In the 85 operation of this form of my invention the inking-frame e is forced downwardly manually, and this operation serves to force the supplemental inking-frame m^3 downwardly, at the same time forcing the main frame c 90 downwardly until the wheels d^2 rest on the roll of paper, and when a strip of paper is withdrawn from said roll the printing-cylinder d is rotated, as previously described, and the inking of the type in the different colors 95 results and the imprint is made on the paper in the manner hereinbefore described. Although I have shown this form of my invention adapted to be manually operated, it will be understood that the same may be operated 100 in a manner similar to that shown in Fig. 3 of the drawings by means of the arm b^2 , the method of forcing the printing-frame downwardly not being the basis of this invention, and any other suitable method of 105 producing this result may be employed. It will therefore be seen that my invention is adapted to print on a roll of paper at predetermined intervals, this printing being accomplished during the withdrawal of a strip 110 of paper from said roll, and said printing is accomplished in both my forms of construction without the blurring due to the type-face being drawn along the paper being printed upon, and while I have shown specific locking devices or devices for intermittently permitting printing it will be obvious that these 115 may be modified materially without departing from the spirit of my invention or sacrificing its advantages, and with this reservation 120

What I claim as new, and desire to secure by Letters Patent, is—

1. In a device for printing upon a roll of paper, a printing-cylinder normally held out 130

- of contact with said roll of paper and adapted to be depressed thereon, an inking-roller normally held out of contact with the printing-cylinder and adapted to be depressed thereon, said printing-cylinder being adapted to be turned by pulling a strip of paper from said roll, and means whereby the inking of the type on the printing-cylinder and the locking of the printing-cylinder at predetermined intervals as well as the releasing of the said cylinder are accomplished by the rotation of the printing-cylinder, substantially as shown and described.
2. In a device for printing on a roll of paper, a main frame adapted to support a roll of paper, a printing-frame pivoted in the top portion of the main frame and tensionally supported above and out of contact with the roll of paper, a printing-cylinder mounted in the printing-frame, an inking-roller also mounted in the printing-frame and tensionally supported out of contact with the printing-roller and adapted to be depressed thereon, said printing-cylinder being adapted to be rotated by pulling a strip of paper from the paper-roll, and means whereby the inking of the type on the printing-cylinder and the locking of said cylinder at predetermined intervals as well as the releasing of the said cylinder are accomplished, substantially as shown and described.
3. In a device for printing on a roll of paper, a main frame adapted to support a roll of paper, a printing-frame pivoted in the top portion of the main frame and tensionally supported above and out of contact with the roll of paper, a printing-cylinder mounted in the printing-frame, an inking-roller also mounted in the printing-frame and tensionally supported out of contact with the printing-roller and adapted to be depressed thereon, said printing-cylinder being adapted to be rotated by pulling a strip of paper from the paper-roll, and means whereby the inking of the type on the printing-cylinder and the locking of said cylinder at predetermined intervals as well as the releasing of the said cylinder are accomplished by the upward movement of the inking-roller, substantially as shown and described.
4. In a device for printing on a roll of paper, a main frame in which said roll of paper is adapted to be placed, a printing-frame pivoted in the top portion of the main frame and tensionally held above the roll of paper when the latter is in position, a printing-cylinder mounted in the printing-frame, a supplemental frame mounted in the printing-frame, an inking-roller mounted in the supplemental frame, means for tensionally supporting the supplemental frame and inking-roller out of contact with the printing-cylinder, means whereby the supplemental frame may be depressed so as to throw the inking-roller into contact with the printing-cylinder, said print-

ing-cylinder being adapted to be rotated by pulling a strip of the roll of paper when the printing-frame is depressed, and means whereby the operation of the printing-cylinder and the inking-roller will be interrupted at intervals, substantially as shown and described. 70

5. In a device for printing on a roll of paper, a main frame in which a roll of paper may be mounted, a shaft supported in the top back portion of the main frame, a printing-frame pivoted on said shaft and tensionally supported above the roll of paper when the latter is in position, an arm connected with one end of said shaft, a printing-cylinder mounted in said printing-frame and adapted to be depressed onto the roll of paper, a supplemental frame pivoted in the printing-frame, an inking-roller mounted in the supplemental frame, means for tensionally supporting the supplemental frame so that the inking-roller 85 will be out of contact with the printing-cylinder, an arm connected with said shaft and adapted to depress the supplemental frame, said printing-cylinder being adapted to be turned by pulling a strip of paper from the roll of paper, and means for interrupting the operation of the printing-cylinder and the inking-roller at intervals, substantially as shown and described. 90

6. In a device for printing on a roll of paper, a main frame, a printing-frame pivotally mounted therein, a printing-cylinder mounted in said printing-frame and rotatable therein, an inking-frame mounted in the printing-frame, an inking-roller in said inking-frame, and devices connected with said inking-frame for locking the rotation of said printing-cylinder against rotation at predetermined intervals, substantially as shown and described. 95

7. In a device for printing on a roll of paper, a main frame in which a roll of paper is mounted, a printing-frame mounted in the main frame and normally supported above the roll of paper, a printing-cylinder mounted in the printing-frame and adapted to be depressed onto the roll of paper, a supplemental printing-frame mounted in the main printing-frame, an inking-roller mounted in the supplemental printing-frame, said supplemental printing-frame being normally supported so 110 that the inking-roller will be out of contact with the printing-cylinder, said printing-cylinder being adapted to be turned by pulling a strip from the roll of paper when the main printing-frame is depressed, and means for 115 interrupting the operation of the printing-cylinder and the inking-roller at intervals, substantially as shown and described. 120

8. A device for printing upon a roll of paper mounted in a suitable frame, a printing-frame pivotally mounted in said main frame, an inking-frame pivotally mounted in said printing-frame, a printing-cylinder rotatably mounted in said printing-frame, an inking-roller rotatably mounted in said inking- 125

65 contact with the printing-cylinder, said print- 130

frame, type arranged on said printing-cylinder, and devices on said inking-frame and printing-cylinder for permitting the contact with said paper and for inking the same at predetermined intervals, substantially as shown and described.

9. In a device for printing on wrapping-paper, a main frame adapted to receive a roll of paper, a printing-frame, a printing-cylinder mounted in the printing-frame, type connected with the printing-cylinder, devices for inking said type, and devices for permitting the contact of said type with said paper at predetermined intervals, said printing-cylinder being adapted to bear on said roll of paper and to be turned by pulling a strip of said paper from said roll, and the devices for inking the type and for permitting the contact of said type with said paper at predetermined intervals being also operated by pulling a strip of paper from the roll, substantially as shown and described.

10. In a device of the class described, a paper-roll frame, a printing-frame, a printing-cylinder rotatable therein, an inking-frame pivotally mounted in said printing-frame and provided with a segment-gear adjacent to the pivotal point thereof, a supplemental inking-frame in said printing-frame also provided with a segment-gear in operative connection with said first-named segment-gear, inking-rollers in said inking-frames, type arranged on said printing-cylinder and devices for permitting the contact of said inking-rollers with said type intermittently, substantially as shown and described.

11. In a device of the class described, a paper-roll frame, a printing-frame, a printing-cylinder rotatable therein, an inking-frame pivotally mounted in said printing-frame and provided with a segment-gear adjacent to the pivotal point thereof, a supplemental inking-frame in said printing-frame also provided with a segment-gear in operative connection with said first-named segment-gear, inking-rollers in said inking-frame, type arranged on said printing-cylinder and devices for permitting the contact of said inking-rollers with said type intermittently, comprising wheels on each of said inking-rollers, corresponding wheels provided with recesses on said printing-cylinder, and means for forcing the wheels on said inking-rollers into the corresponding recesses of the wheels on said printing-cylinder, substantially as shown and described.

12. In an apparatus of the class described, a main frame adapted to receive a roll of paper,

a printing-frame pivoted in the main frame and normally held out of contact with said roll of paper and adapted to be depressed thereon, printing devices mounted in the main frame and adapted to be depressed onto the roll of paper when the printing-frame is depressed, and two inking-rollers mounted in the printing-frame and normally supported above the printing devices and adapted to be depressed thereon, substantially as shown and described.

13. In an apparatus for printing on wrapping-paper, a main frame adapted to receive a roll of paper, a printing-frame pivoted in said main frame and normally supported above the paper and adapted to be depressed thereon, a printing-cylinder mounted in the printing-frame and adapted to bear on the roll of paper when said frame is depressed, an inking-roller mounted in the printing-frame and adapted to be depressed onto the printing-cylinder, and inking devices mounted in said printing-frame and operating in connection with said inking-roller, and devices mounted in said printing-frame and operating in connection with said printing-cylinder and inking-roller for printing on said paper in different colors, said printing-cylinder, inking-roller and devices being adapted to be operated by pulling a strip of paper from said roll, substantially as shown and described.

14. In an apparatus of the class described, a main frame adapted to receive a roll of paper, a printing-frame pivoted therein and tensionally supported above the roll of paper and provided with a printing-cylinder adapted to be depressed thereon, inking-rollers mounted in the printing-frame and adapted to be depressed onto the printing-cylinder, inking devices mounted in the printing-frame and operating in connection with the inking-rollers, and other devices mounted in the printing-frame and operating in connection with the printing-cylinder and inking-rollers for printing on the paper in different colors, said cylinder, inking-rollers and devices being adapted to be operated by pulling a strip of paper from said roll, substantially as shown and described.

In testimony that I claim the foregoing as my invention I have signed my name, in presence of the subscribing witnesses, this 10th day of November, 1905.

PAUL THEODORE HAHN.
